ATTORNEY

UNITED STATES PATENT OFFICE.

THOMAS LAWLER AND JOHN J. LAWLER, OF CLIFTON, NEW YORK.

EXCAVATING-BUCKET.

SPECIFICATION forming part of Letters Patent No. 378,099, dated February 21, 1888.

Application filed March 12, 1887. Serial No. 230,712. (No model.)

To all whom it may concern:

Be it known that we, THOMAS LAWLER and JOHN J. LAWLER, citizens of the United States, and residents of Clifton, in the county of Rich-
mond and State of New York, have invented
certain new and useful Improvements in Ex-
cavating-Buckets, of which the following is a
specification.

Our invention relates to that class of dredge
excavating-buckets known as "clam-shell" or
"grapple" buckets. The special object of our
bucket is to operate in hard or compact ma-
terial, such as sand or clay, where the present
class of such buckets will not operate, owing
to the inability to force or hold the buckets
into the material. This we accomplish by
bringing the grapping parts of the bucket onto
a cylinder having the operating parts mounted
thereon, and the said cylinder provided with
a piston working within the cylinder, which
raises the material in its upward movement,
and by the vacuum thus formed the cylinder
is held down on the material, so we are en-
abled to force the grapple-scoops into the ma-
terial, which close under the bottom and re-
tain the load while being raised from the bot-
tom, which will be hereinafter more fully ex-
plained, reference being had to the accom-
panying drawings, in which—

Figure 1 represents side elevation of our
bucket as closed when loaded, part in section.
Fig. 2 represents same when open for dis-
charging the load and ready to lower on the
material for another load.

A is the cylinder in which the piston B is
fitted, same being provided with a packing,
2, of any suitable material, to make said pi-
stion air-tight in similar manner as the piston
of a pump. To the top of said piston B are at-
tached the toothed racks C and C', respect-
ively, on the upper end of which is secured
the cross-head guide D, through which the
operating-chains pass, being guided by suit-
able rolls, 3 4 5 6. Engaging with the racks
C and C' are the gear-wheels E and E', mounted
on suitable arms, 7 and 8, secured to the out-
side of cylinder A at b, the said wheels E and
E' being connected to the pivoted grapple-
scoops F and F' by the rods 10 and 11, hinged
to the outer edge of same at C. The said scoops
are secured to the outside of the cylinder A
at 12 on pivots or trunnions.

G and G' are the hauling-chains for closing
the grapple-scoops F and F' and raising the
load.

H and H' are backing-chains for opening
same when raised to point of discharge and
for lowering said bucket onto the material, as
shown in Fig. 2.

The operation is: The bucket being open, as
shown in Fig. 2, the said bucket is lowered by
the chains H and H' onto the material. The
edge of the cylinder A will force itself into
same until it rests on the piston B. The cut-
ting-edges 13 and 14 of the scoop-grapples will
also enter to the same depth. The chains H
and H' are then slackened and the power ap-
plied to the chains G and G', which are secured
to the wheels E and E', respectively, and pass
under sheaves 15 and 16, (secured on the
top of piston B,) thence up between the racks
C and C', through the cross-head D, to the
point of power. As the said chains G and G'
are drawn up, they raise the piston B in the
cylinder A, drawing the material into same,
and at the same time force the pivoted grap-
ple-scoops F and F' into the material, as shown
by dotted lines in Fig. 2, by the rods 10 and
11, which are actuated by the wheels E and E',
the said wheels being revolved by engagement
with the toothed racks C and C' and the chains
G and G', this motion continuing until the
scoops are closed and the piston B is at the
top of the cylinder A, as shown in Fig. 1,
where it will be found that the cylinder A and
scoops F and F' are full. The whole being
raised to point of discharge, the chains G and
G' are slackened and the power applied to the
chains H and H', (which are also secured to
the wheels E and E', respectively,) revolving
the said wheels E and E' in the opposite di-
rection, opening the scoops F and F' and forc-
ing the piston B downward, as shown in Fig.
2, removing the load if it should have any
tendency to adhere to the cylinder A, when
the bucket is then ready to repeat the above-
described operation.

When the bucket is open, as shown in Fig.
2, the pivoted grapple-scoops F and F' are
outwardly inclined at the bottom for the pur-
pose of allowing the material to be discharged
from them freely and to form a better cut-
ting-edge when lowered onto the material.
Thus it will be seen by the powerful com-

pounding of the power by means of the toothed racks C and C' engaging with the wheels E and E', to which the hauling-chains G and G' are also attached, we are able in hard and compact material, which will not rise in the cylinder A, to hold said cylinder firmly down to the work by the suction of the piston B, while the grapple-scoops F and F' are forced into the material and disengage sufficient quantity to fill the whole bucket.

If desired, the lower edge, e, of the cylinder A may be serrated, and also the cutting-edge of the scoops F and F', to enable the same to more readily enter the material.

Having described our invention, what we claim, and desire to secure by Letters Patent, is—

1. In an excavating-bucket, the cylindrical tube A, open at both ends and provided with the piston B, working freely in the said cylinder A, in combination with the grapple-scoops F and F', pivoted to the said cylinder A and closing under same, substantially as and for the purpose specified.

2. In an excavator-bucket, the cylinder A, having a piston, B, provided with toothed

racks C and C', and said racks engaging with the wheels E and E', connected at their upper end with cross-head D, substantially as and for the purpose specified.

3. In an excavator-bucket, the wheels E and E', mounted on the cylinder A and engaging with toothed racks C and C', and having the hauling-chains G and G' and backing-chains H and H' attached to said wheels, and the wheels being connected to the scoops F and F' by the rods 10 and 11, substantially as and for the purpose specified.

4. In an excavator - bucket, the hauling-chains G and G', passing under the sheaves 15 and 16, secured to the top of piston B, and the said chains connected to the wheels E and E', mounted on the cylinder A, substantially as and for the purpose specified.

Signed at New York, in the county of New York and State of New York, this 8th day of March, A. D. 1887.

THOS. LAWLER.
JOHN J. LAWLER.
